UNITED STATES PATENT OFFICE.

PAUL M. LINCOLN, OF PITTSBURGH, PENNSYLVANIA.

ENGINE-STARTER.

1,280,776.

Specification of Letters Patent.

Patented Oct. 8, 1918.

Application filed March 24, 1914. Serial No. 826,903.

To all whom it may concern:

Be it known that I, PAUL M. LINCOLN, a citizen of the United States, residing at Pittsburgh, in the State of Pennsylvania, have invented certain new and useful Improvements in Engine-Starters, of which the following is a specification.

My invention relates to starting devices for explosive engines, and particularly an electric motor starter; its primary object being to employ an electric motor for making the initial turns of the engine shaft, whereupon the active motion of the engine shaft releases the connection, the invention having the specific object of rendering such devices more accurate and economical in operation. I have illustrated an embodiment of my invention in the accompanying drawing, which is a partial side elevation and partial section with diagrams and electric connections.

As shown in the drawing, I attach to the motor 1, an extended casing 2 into which projects the engine shaft 8^a carrying the worm gear 8 and which also carries an extension boxing 3, in which are the bearings 4 of an extension of the motor shaft 5. This extension is in the shape of a hollow square shaft 6, mounted upon which is a sliding worm gear 7 intermittently engaging the gear 8 on the explosive engine shaft. It will be apparent that when the motor is turning its shaft including the square extension 6, and the worm is in engagement with the worm gear 8, the worm 7 will revolve the engine shaft, in the direction as marked by the arrow, and when an explosion occurs in the engine and the shaft 8^a becomes active, the wheel 8 will throw the worm 7 back to the left and disengage the motor shaft. My present improvements relate more especially to the means of carrying out the operation of engagement with certainty and smoothness and safety.

On the hollow square shaft 6, to the right of engagement position of the gear 7, I place a spiral buffer spring 9 to prevent hammering of the parts, when on account of the expansion of a compressed and non-exploding charge in the engine cylinder the gear 8 may cause the worm 7 to be temporarily thrown to the left without totally disengaging same. Within the square shaft 6, I also place a coil compression spring 12,

which normally holds the worm 7 in disengaged position to the left. By means of a flattened pin 11, extending through slots in the shaft 6, the worm 7 is attached to a sliding extension 10 which at its outer end carries a solenoid plunger 13, working within a dashpot barrel 14, and forming the core of the electromagnet 15. This solenoid operates to push the shaft 10 and gear 7 to the right as now shown, by the closing of the switch 17 on the contact 18, thereby putting the battery 16 in circuit with the motor leads 21, 22, and the leads to the solenoid 15.

It will be noted therefore that in the original starting of the motor, the circuit contains the resistance of coil 15 and this coil preferably has high resistance, so as to keep down the flow of the current through the motor 1 and causes it to start comparatively slowly, the solenoid absorbing most of the energy in moving the plunger to the right in order to engage the gear 7. During this period of action the motor needs only enough power to turn it and move the worm 7. After the engagement of the worm with wheel 8 however, and in the working position of the parts, the solenoid is no longer of any use, and meantime the motor is called upon for much heavier work. With this in view I short-circuit the solenoid coil at the proper moment, showing in the drawing a convenient means which consists of the insulated switch bar 23 attached to a spring return plunger 23^a which normally rests upon the plunger 13, but is allowed to rise when the plunger has passed the proper position, thus connecting the contacts 24, 24^a, respectively connected to the leads of the solenoid. It is evident that this contact cannot be made until worm 7 is entirely engaged with gear wheel 8.

Of course the starting of the engine will throw out the worm 7; but even if the switch 17 is still depressed, the motor is taking a reduced current from the battery and on account of this reduction in current the solenoid will not be strong enough to push the worm back into mesh. The counter-electromotive force of the now running motor will keep down the current; and it will be understood that I intend the solenoid 15 to be so designed as not to actuate the worm with such reduced current. The spring 19 attached to the switch 17, is adjustable by a

screw 20 and is so designed that it will retract the switch entirely when the motor is running.

It will be understood that the solenoid 6 plunger 13 is made to fit the casing 14 close enough to form an air dashpot, to prevent too sudden movements of the plunger and worm 7 in either direction, and of course the spring 12 normally keeps the worm out 10 of engagement. The various advantages of this arrangement will be apparent to those skilled in the art.

Having thus described my invention and illustrated its use, what I claim is:

- 16 1. An explosive-engine starter comprising the combination with a gear member on the engine shaft, of an electric motor having a sliding gear member on its shaft, a solenoid having its core also on the shaft and 20 in circuit with the motor and a battery and adapted to move said sliding gear member into temporary engagement with said gear, cushioning means for said sliding gear member and resilient means for holding it normally 25 in its out-of-mesh position.
2. In a starting device for an explosive engine, the combination with a gear member on the engine shaft, of an electric motor provided with a gear member on its shaft that 30 is movable longitudinally into and out of mesh with the engine-shaft gear member, a solenoid in circuit with the electric motor and having a core that is movable to effect temporary engagement of said gear members, cushioning means for said movable 35

gear member and a switch for simultaneously closing the solenoid and the motor circuits, substantially as described.

3. An engine starter comprising a motor and a shaft and gearing adapted to temporarily engage and rotate the engine shaft, a supplemental shaft sliding in, but turning with, the motor shaft, a solenoid having its core attached to said supplemental shaft, an electric circuit and a switch adapted to first 40 make the circuit through the solenoid coil and the motor windings and a switch adapted to afterward short-circuit the solenoid, substantially as and for the purpose described. 45

4. An engine starter, comprising a motor and means for effecting a temporary operative connection whereby the motor first turns the engine shaft and is disconnected therefrom when the engine becomes self-operating, a buffer spring for receiving the impact of a movable member of said means as it moves into operative position, a spring for holding said member normally in a non-operative position, an operating solenoid 50 and means for checking the movements of the solenoid core, substantially as described. 55

In testimony whereof I have hereunto signed my name in the presence of the two subscribed witnesses.

PAUL M. LINCOLN.
